UNITED STATES PATENT OFFICE.

SAMUEL BERMAN, OF CHICAGO, ILLINOIS, ASSIGNOR TO THE SCHOLL MFG. CO., INC., OF CHICAGO, ILLINOIS, A CORPORATION OF NEW YORK.

METAL-POLISHING MACHINE.

Application filed December 2, 1925. Serial No. 72,724.

This invention relates to an improved metal polishing machine adapted to afford a convenient arrangement for the buffing of strips of German silver or other metal material which, when advanced into the machine over a reciprocating table, are brought into the field of operation of a rotatable buffing mechanism which acts to efficiently polish the entire surface of the strip of metal.

It is an object of this invention to provide an improved metal polishing machine adapted to buff the surface of a strip or bar of metal as it is advanced through the machine with a composite movement below a rotatable buffer by means of a reciprocating table and feeding means on said table.

It is also an object of this invention to provide an improved buffing machine wherein a reciprocating table is provided with feeding mechanisms for the purpose of advancing a sheet of metal below a rotatable buffer adapted to act transversely of the line of movement of the strip of metal through the machine.

It is an important object of this invention to provide an improved buffing machine wherein a rotatable buffer is adapted to act on a strip of metal as the strip of metal is advanced longitudinally through the machine by feeding mechanisms carried on a reciprocating table, the direction of motion of which is transversely to that of the strip of metal through the machine thereby imparting a composite movement to the strip of metal as it is acted upon by the rotating buffer.

Other and further important objects of this invention will be apparent from the disclosures in the specification and the accompanying drawings.

This invention (in a preferred form) is illustrated in the drawings and hereinafter more fully described.

On the drawings:

- Figure 1 is a top plan view of a metal polishing machine embodying the principles of this invention with the metal supporting table at the feeding end of the machine omitted;
- Figure 2 is a side elevation of the machine with parts shown in section and with parts broken away;
- Figure 3 is an end elevation of the machine taken on line III—III of Figure 2;
- Figure 4 is an enlarged fragmentary side elevation of the reciprocating table and its support taken on line IV—IV of Figure 1 showing parts in section;
- Figure 5 is a transverse section taken on line V—V of Figure 4;
- Figure 6 is a side elevation of the material supporting table at the feeding end of the machine shown connected to a fragmentary portion of the machine proper;
- Figure 7 is an enlarged detail section taken on line VII—VII of Figure 6;
- Figure 8 is an enlarged detail sectional view taken on line VIII—VIII of Figure 6; and
- Figure 9 is an enlarged fragmentary detail view taken on line IX—IX of Figure 6.
- As shown on the drawings:
- The reference numeral 1 indicates a machine base or framework having securely mounted longitudinally on the top thereof a driving motor 2 having a buffing wheel 3 engaged on one projecting end of the motor shaft 4. Secured on the other projecting end of the motor shaft 4 is a pinion 5 which is in mesh with a pinion 6 on a shaft 7 of a gear reducing mechanism 8. Securely mounted on the second projecting end of the gear reduction shaft 7 is a sprocket 9 around which an endless chain 10 is trained. The driving chain 10 is also trained around a sprocket 11 which is securely mounted upon a shaft 12 journalled in suitable bearings 13 secured on the rear side of the machine framework 1. Mounted on the shaft 12 adjacent the sprocket 11 is a pawl-clutch 14 adapted to be operated by a clutch lever 15. Mounted on one end of the shaft 12 is a slotted eccentric block 16 provided with suitable graduations—as shown in Figure 3—to permit an eccentric pin 17 to be adjustably secured in different positions with respect to the eccentric 16 for the purpose of varying the stroke of a reciprocating table 18. Pivotally connected to the lug or arm 19 of the reciprocating table 18 is one end of an eccentric connecting rod 20, the other end of which is pivotally engaged on the eccentric pin 17, as clearly illustrated in Figure 3.
- The horizontally reciprocating table 18 is slidably engaged upon a dove-tail guide 21 integrally formed longitudinally upon the top of a vertically adjustable supporting table 22 which is vertically slidably mounted upon a suitable guide 23 formed on the

feeding end of the machine framework 1. A raising and lowering mechanism for the table 22 is provided and comprises a rotatable lifting screw 24 having a bevel gear 25 keyed on the lower end thereof with said bevel gear 25 meshing with a bevel gear 26 mounted on a stub shaft 27. The stub shaft 27 is journaled in a suitable bearing 28, as clearly shown in Figure 2. Engaged on the outer end of the stub shaft 27 is a wheel 29 provided with a handle 30. It will thus be noted that by operation of the wheel 29 the supporting table 22 may be adjusted vertically with respect to the machine framework 1 so that the reciprocating table 18 on the table 22 may be raised or lowered with respect to the buffing wheel 3.

Securely mounted upon the top of the supporting table 22 are two pairs of bearing brackets 31 in which a pair of parallel shafts 32 are journaled. The shafts 32 project through the lower portions of bearing yokes 33 which are rigidly secured upon the top of the reciprocating table 18. Each of the shafts 32 is provided with two diametrically opposite keys 34 upon which are slidably engaged lower material feed rollers 35. The lower feed rollers 35 are adapted to reciprocate with the reciprocating table 18 with said lower feed rollers having a sliding movement longitudinally with respect to the rotatable shafts 32. Engaged on one end of each of the lower feed rollers 35 is a gear 36 which meshes with an upper gear 37 engaged on one end of an upper material feed roller 38. It will thus be noted that the two upper material feed rollers 38 are adapted to receive a drive from the lower feed rollers 35. The upper feed rollers 38 are mounted on shafts 39, the ends of which are journaled in suitable bearing blocks 40 which are slidably engaged in the bearing brackets 33. Springs 41 are mounted in the bearing brackets 33 above the slidable bearing blocks 40 for the purpose of resiliently holding the bearing blocks in a lowered position. Adjusting screws 42 are provided in the top of each of the bearing brackets 33 for the purpose of adjusting the tension of the springs 41.

Engaged on the outer rear end of each of the shafts 32 is a spiral gear 43 adapted to be driven by a small spiral gear 44. The two spiral gears 44 are mounted upon a shaft 45 journaled in suitable bearings 46 upon the top of the rear end of the supporting table 22.

Connected to one end of the shaft 45 is a universal coupling or joint 47 which is also connected to a solid universal shaft 48 which telescopes into a hollow universal shaft 49. Connected to one end of the hollow universal shaft 49 is a universal joint or coupling 50 which is also connected to one end of a stub shaft 51 journaled in a suitable bearing 52 mounted upon the machine framework 1. Secured on the outer end of the stub shaft 51 is a large gear 53 which receives a drive from a meshing small gear or pinion 54 which is secured on one end of the driving shaft 12. It will thus be seen that the material feed rollers 35 and 38 are adapted to be driven from the shaft 12 through the large gear 53 and the universal shaft mechanisms which operate the spiral gears 44 and 43 to cause rotation of the shafts 32 on which the lower feed rollers 35 are slidably keyed.

A strip of German silver or other metal 55, which is to be polished or buffed, is admitted into the machine over a shiftable material supporting runway or table comprising (as illustrated in Figure 6) a slotted clamping plate 56 which is bolted securely to the outer side of the reciprocating table 18. Integrally formed on the clamping plate 56 is an outwardly projecting sleeve 57 in which one end of a rod or shaft 58 is secured. The outer end of the shaft 58 projects through a sleeve 59 which is integrally formed beneath a transverse sleeve 60. The two sleeves 59 and 60 are disposed at right angles to one another with the upper sleeve 60 being integrally formed on the under side of a table bracket 61 provided with an integral flange 62 at one end thereof. The top surface of the table bracket 61 is in a plane with the meeting surfaces of the feed rollers 35 and 38. The table bracket 61 is supported in position by means of a transverse pin or shaft 63 which projects through the sleeve 60 of the table bracket 61. The pin 63 is mounted to have the ends thereof projecting through slots 64 in guide arms 65 which are integrally formed on the upper end of a pedestal or standard 66. The pin 63 is adapted to be removably clamped in an adjusted position with respect to the slotted arms 65 by means of a clamping handle 67. This arrangement is provided for the purpose of permitting the outer end of the material feed table to be adjusted vertically with corresponding adjustments of the supporting table 22 and the reciprocating table 18. Securely mounted at spaced intervals on the shaft 58 are the sleeves 68 of intermediate table brackets 69 over the top of which the material 55 is adapted to be fed into the machine. The intermediate table brackets 69 are provided with an end flange 70 which, together with the end flange 62 on the table bracket 61, afford guides or stops for the strip of material as it is advanced into the machine.

The material after being polished or buffed by the buffing wheel 3, is advanced over the reciprocating table 18 and passes longitudinally through the machine over a reciprocating discharge table mechanism,

which is also connected to the reciprocating table 18. The discharge table or support for the polished material comprises a bracket 71 which is bolted to the inner side of the reciprocating table 18, as illustrated in Figure 2. Supported in the bracket 71 is one end of a table shaft 72, the other end of which is supported in a bracket 73 similar in construction to the table bracket 59—62 illustrated in Figure 9. The table bracket 73 is slidably mounted on a shaft or pin 74 which is vertically adjustable in slotted guide members 75 formed on the machine frame. The shaft 74 is adapted to be clamped in an adjusted position by means of a clamping handle or lever 76. Mounted on the table shaft 72 are a plurality of spaced intermediate table brackets 77 provided with suitable guide flanges or stops for the material 55. The table brackets 77 are constructed similar to the table brackets 69 illustrated in Figure 8. It will thus be seen that the strip of material 55 is adapted to be advanced over a reciprocating entrance feed table, then over the reciprocating table 18 between the feed roller mechanisms, and is finally discharged through the machine over the reciprocating discharge table mechanism.

30 The operation is as follows:

The improved buffering or metal polishing machine of this invention is adapted to be set in operation by means of a control switch 78 which governs the operation of the driving motor 2. With the motor 2 set in operation, the buffering wheel 3 is rotated at a high rate of speed and the drive from the motor 2 is transmitted through the speed reduction mechanism 8 to the chain 10 which drives the shaft 12. The drive from the shaft 12 is transmitted through the pinion 54 and the gear 53 to the universal shaft mechanisms to cause rotation of the shafts 32 which serve to rotate the lower feed rollers 35. The eccentric 16, rotated by means of the shaft 12, causes operation of the eccentric connecting rod 20, which in turn acts to reciprocate the table 18 upon the supporting bracket or table 22. With the buffering wheel 3, the reciprocating table 18 and the material feed rollers set in operation as hereinbefore described, a strip of German silver, or other metal 55, is positioned upon the outer feed table brackets 61 and 69 (Figure 6) and is guided into the machine by means of the guide flanges 62 and 70 on the table brackets. The table brackets being mounted on the shaft 58, reciprocate with the table 18 thereby permitting the inner end of the material 55 to be pushed between the first pair of feed rollers 35 and 38 which act to gradually advance the strip of material over the reciprocating table in the field of operation of the buffering wheel 3. The two pairs of feed rollers act to advance the sheet of material longitudinally through the machine, pulling the same over the outer or feed table mechanism across the reciprocating table 18 and then discharging the same over the discharge table mechanism after the rapidly rotating buffering wheel has polished the upper surface of the strip of material. The material is thus advanced over a continuously reciprocating table mechanism comprising the outer table, the intermediate table 18 and the inner table. The strip of material 55, as described, is adapted to be advanced longitudinally through the machine beneath the rapidly rotating buffering wheel 3 by means of the feed roller mechanisms 35—38 and simultaneously with the longitudinal advance of the material, said material is adapted to be reciprocated transversely of the machine by means of the reciprocating table 18 and its extensions. The material is thus advanced through the machine with a composite movement relative to the rapidly rotating buffering wheel 3 which frictionally engages the upper surface of the strip of material and rapidly buffs or polishes said surface. All parts of the upper surface of the strip of material are quickly and efficiently buffed as the material is fed through the machine. The buffed or highly polished strip of material 55 is adapted to be discharged from the machine over the discharge table extension shown in Figure 2.

For the purpose of buffering strips of material of different thicknesses, the reciprocating feed table and its extensions may be adjusted vertically by means of the screw 24 operable by the wheel 29, said screw adapted to either raise or lower the supporting table 22 with respect to the machine frame so that the reciprocating table 18 may be adjusted vertically with respect to the buffering surface of the buffering wheel 3. The outer and inner table extensions of the reciprocating table 18 are adapted to be adjusted with respect to their stationary supports by means of the clamping mechanisms 67 and 76, respectively. The vertical adjustment of the reciprocating table mechanism also affords a means for compensating for the wear of the peripheral surface of the buffering wheel 3.

The drive from the speed reduction gear mechanism 8 by means of the chain 10 to the material feed mechanisms on the table 18 and the eccentric mechanisms governing the reciprocation of the table 18 are controlled by means of the clutch 14 and the clutch lever 15.

I am aware that many changes may be made, and numerous details of construction may be varied through a wide range without departing from the principles of this

invention, and I therefore do not purpose limiting the patent granted hereon, otherwise than necessitated by the prior art.

I claim as my invention:

- 5 1. A metal polishing machine comprising a frame, a vertically adjusted bracket mounted on said frame, a driving motor mounted on said frame, a buffing wheel mounted on one end of the motor shaft, a speed reduction mechanism mounted on said frame, gear means for connecting the same to the other end of the motor shaft, a table slidably mounted on said bracket, extension shafts secured to opposite sides of said table, material supporting brackets on said extension shafts, supports for slidably supporting the outer ends of said extension shafts, material feed mechanisms mounted on said table, means for driving the same from said speed reduction mechanism to cause material on the material supporting brackets on one side of the table to be advanced over said table beneath the buffing wheel and then over the material supporting brackets on the opposite side of said table, and drive transmitting means connecting the speed reduction mechanism with said table to cause the table, the extension shafts and the material supporting brackets to be reciprocated, to cause 25 the material being advanced through the machine to have a composite movement.
2. A material polishing machine comprising a frame, a buffing wheel mounted thereon, means for driving the same, a vertically adjustable table support on said frame, a reciprocating table on said table support adapted to be actuated by said driving means, table extensions projecting from op- 30 35 40 45 50 55 60 65 70 75

posite sides of said reciprocating table, supports for slidably supporting the ends of said table extensions, and material feed means on said reciprocating table adapted to be operated from said driving means to cause a material to be advanced over the table extensions and said table and through the field of operation of the buffing wheel to cause polishing of the material.

3. In a metal polishing machine the combination with a framework, of a table support vertically adjustable thereon, a reciprocating table on said table support, table extensions connected to opposite sides of said table, supports for slidably supporting the ends of said table extensions, and means permitting vertical adjustment of said supports whereby the table extensions may be adjusted vertically with the vertical adjustment of the reciprocating table.

4. In a metal polishing machine the combination with a framework, of a table support slidably mounted thereon, means for vertically adjusting the table support, a reciprocating table on said table support, means for operating the same, table extensions secured to opposite sides of the reciprocating table, supports for slidably supporting the ends of said table extensions, and means permitting vertical adjustment of said supports to permit the table extensions to be adjusted vertically with the reciprocating table when the reciprocating table support is vertically adjusted with respect to the framework.

In testimony whereof I have hereunto subscribed my name.

SAMUEL BERMAN.
